UNITED STATES PATENT OFFICE.

CHARLES W. McGONIGLE, OF NORTH YAKIMA, WASHINGTON, ASSIGNOR OF ONE-HALF TO
O. L. YOUNG, OF NORTH YAKIMA, WASHINGTON.

ENGINE.

No. 870,308.

Specification of Letters Patent.

Patented Nov. 5, 1907.

Application filed October 31, 1906. Serial No. 341,461.

To all whom it may concern:

Be it known that I, CHARLES W. McGONIGLE, a citizen of the United States, residing at North Yakima, in the county of Yakima and State of Washington, have invented a new and useful Engine, of which the following is a specification.

This invention relates to apparatus for the production of gases under pressure to be utilized for motive power, and has for its principal object to provide an apparatus in the nature of an internal combustion engine in which gas under pressure and steam may be generated and utilized directly in the operation of a rotary or turbine engine.

A further object of the invention is to provide an apparatus which will operate steadily and without the noise and shock incident to ordinary engines of the explosive type.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a side elevation, partly in section, of an apparatus constructed in accordance with the invention. Fig. 2 is a transverse sectional view of the engine proper on the line 2—2 of Fig. 1. Fig. 3 is a vertical section of the engine on the line 3—3 of Fig. 2. Fig. 4 is a detail sectional view of one of the thermostatically actuated valves.

Similar numerals of reference are employed to indicate corresponding parts throughout the several figures of the drawings.

In carrying out the invention, a comparatively large cylinder 10 is provided at one of its sides with a bearing opening for the reception of a shaft 11, and to the shaft is secured a revolute piston 12, that is provided with a plurality of vanes or buckets 13 which may be curved, as shown in Fig. 2. Extending within the annular row of blades or vanes is an annular chest 14 that is rigidly secured to the stationary side wall or head of the cylinder, and this chest is provided with a plurality of ports 15, through which the actuating fluid is directed against the vanes 13 for the purpose of revolving the piston.

Secured to the cylinder and in direct communication with the annular chest 14 is a generating chamber 20 that is preferably in the form of an elongated cylinder, the longitudinal axis of which is coincident with the axis of the shaft. This cylinder is formed of any suit-

able material, and in practice will be jacketed in the same manner as the cylinder of an ordinary internal combustion engine.

Extending into the cylinder is a series of burners 22 which may be connected to any suitable source of gas supply, each burner having a suitable regulating valve 23. The air to support combustion is admitted through a pipe 24 preferably from a suitable compressed air reservoir, and said pipe 24 is connected to a helically wound perforated coil 25, so that the air may become highly heated within the coil and then discharged in minute jets all around the burners, the quantity of air being greatly in excess of that required to support combustion, and such air becoming highly heated and intermingling with the products of combustion to form a gas under a pressure sufficient to operate the engine.

In order to reduce the temperature within the generating chamber to some extent, and to add to the volume and pressure of the operating fluid, a water supply nozzle 25 is introduced into the chamber at a point between the burners and the engine, and water is forced under pressure through this chamber, the water being instantly flashed into steam, which, being intermingled with the air and gases, will add materially to the volume and pressure of the actuating fluid.

The air pipe 24 is provided with a valve 28 that is under the control of a thermostat 29, so that when the heat becomes excessive, the valve may be closed to a greater or less extent by the operation of the thermostat and in similar manner the water jet supply pipe has a thermostatically operated valve 30 for governing the supply of water.

Fig. 4 illustrates one form of thermostatically actuated valve for controlling the water or air supplies. The casing 30 is provided with a partition 31 having a double conical seat 32, one for receiving the manually actuated valve 33 and the other the thermostatically actuated valve 34. The valve 34 is attached to a spring pressed piston 35 working in the cylinder 36 of the casing 30. This piston is actuated by a column of mercury contained in the tubular thermostat 29, and as the mercury expands under the increased temperature of the air in the pressure chamber, the valve 34 is caused to close so that the supply of air or water, as the case may be, is cut off. As soon as the temperature falls to a predetermined limit, the valve 34 will open to restore the supply of air or water. When it is desired to positively cut off the supply, the manually actuated valve 33 is closed.

In order to ignite the gas an ordinary form of electric sparkler 40 may be used as indicated in Fig. 1.

With an apparatus constructed in accordance with this invention, steady and uniform power may be attained at comparatively small expense, and the oper-

2
ation may be carried on without the noise and jar incident to the operation of ordinary engines of the explosive type.

I claim:-

- 5 1. The combination with an engine, of a pressure chamber in permanent communication therewith, a perforated conduit arranged helically within the chamber, a plurality of burners disposed within the chamber in proximity to the conduit to receive air therefrom for supporting combustion, means for supplying air to the conduit in excess of the amount required to support combustion to be heated by the burners, and an automatic means sensitive to the temperature of the air within the chamber for controlling the air supply.
- 10 15 2. In combination, a turbine engine, a fluid pressure generating chamber in direct communication therewith, a

gas burner in the chamber, a perforated air pipe coiled within the chamber, and means for forcing air under pressure through said pipe.

3. The combination with a turbine engine, of a pressure chamber in direct communication therewith, a perforated tube arranged in a helical coil within the chamber, means for forcing air under pressure through said tube, a gas burner arranged within the chamber and serving to heat and expand the air, and a water jet pipe extending within 25 the chamber at a point in advance of the burner.

In testimony that I claim the foregoing as my own, I have hereto affixed my signature in the presence of two witnesses.

CHARLES W. McGONIGLE.
